UNITED STATES PATENT OFFICE.

LEROY WEEKS, OF NEVADA, IOWA.

SYSTEM OF KILNS.

Application filed June 12, 1922. Serial No. 567,608.

To all whom it may concern:

Be it known that I, LEROY WEEKS, a citizen of the United States, and a resident of Nevada, in the county of Story and State 5 of Iowa, have invented a certain new and useful System of Kilns, of which the following is a specification.

The object of my invention is to provide a system of kilns for drying and burning 10 ware, which is simple, durable, inexpensive, and comparatively simple in operation.

More particularly, my invention relates to a battery of kilns arranged so that the heat from one of the kilns may be discharged 15 into the next adjacent kiln and so on, whereby a great efficiency in the use of fuel may be obtained.

Still another object is to arrange a subterranean conduit for connecting each pair of 20 the adjacent kilns so that a fan member may be selectively and removably mounted in any one of the conduits so that the heated air from one kiln may be drawn into the next adjacent kiln, and after the temperature 25 of the latter kiln reaches a predetermined degree, the fan element may be removed for preventing it from melting down, and for using it one of the other conduits.

In this connection it may be mentioned 30 that were the fan element permitted to remain in the conduit and a fan element were provided for each conduit, then after the heat passing from one kiln to the other, reached a certain degree, the fan element 35 would melt down and when the heat reached the proper degree for burning the ware in the kiln it would be so hot that the fan would be worthless. The revolving fan would commence to weaken at approximately 40 six or seven hundred degrees, while the heat passing from one kiln to the other might reach twenty-two or twenty-three hundred degrees, and it can, therefore, be seen why it is necessary to remove the fan element 45 from the conduits.

In this connection it will also be seen that by arranging the fan element so that it will be selectively or removably mounted in any one of the conduits makes it possible 50 to use one fan element for a battery of kilns.

With these and other objects in view, my system of kilns consists in the construction, arrangement and combination of the various parts of my device, whereby the objects contemplated are attained, as herein-after more fully set forth, pointed out in my claim and illustrated in the accompanying drawings, in which:

Figure 1 is a battery of kilns, one of the 60 kilns being shown in section to illustrate the construction thereof.

Figure 2 is a vertical, central sectional view taken on line 2—2 of Figure 1.

Figure 3 is a plan view of a portion of 65 the conduit passing from one kiln to the next adjacent kiln; and

Figure 4 is a detailed, sectional view taken on line 4—4 of Figure 3 showing the mounting of the fan element.

In the accompanying drawings, I have used the reference numeral 10 to indicate a kiln of the ordinary construction. In order to clearly understand the construction of the kilns, I will now describe in detail one 75 of them.

The kiln 10 is provided with walls which project down into the ground some distance, as clearly shown in Figure 2 of the drawings. The kiln 10 is provided with what is 80 commonly known as a flash wall 11. Arranged between the flash wall 11 and the walls of the kiln 10 are the partitions 12, which form the space between the flash wall 11 and the outer wall of the kiln 10 into the 85 passage way and flues, as will hereinafter more fully be explained.

The kiln 10 is provided with a floor structure 13 which is of the grate type so that air may pass in below the floor 13. A 90 passageway 14 is arranged below the floor 13 which is in communication with the subterranean conduits 15.

Below the partition members 12 is the annular heating chamber 16. In order to 95 properly "fire" the kilns, it is necessary that grates 17 be provided, which may be horizontal or inclined as desired. The grates are so arranged that they are mounted in the flash wall 11 and the outer wall of the kiln 100 10, between a pair of the partition members 12.

The portion between the partition members 12 and above the grates 17 may be properly termed the flues 18. The flues 18 are alternately arranged with passage ways 19. The passage ways 19 are in communication with the annular heat chambers 16, while the flues 18 are separated from the heat chambers 16 by means of the partition 20.

The conduit 15 is in communication with the smoke stack 21, having a damper 22 arranged therein. The conduit 15 is also provided with a damper structure 23.

I will now describe the ordinary "firing" operation of the ordinary kiln. Each of the grates 17 are stacked with burning coals and the heat is permitted to pass up through the flues 18, as indicated by the arrow 24. The products of combustion then pass in through the ware located within the kiln 10 and through the openings in the floor 13, and through the passage ways extending on each side of the passage way 14, as indicated by the arrows 25. The products of combustion then pass through the conduit 15 and out through the stack 21.

In this connection it may be mentioned that a great deal of heat is lost by this method and in order to use the products of combustion, which ordinarily pass up through the stack 21, I arrange the conduits 15 so that they are in communication with the next adjacent kiln 10. In order to draw the heat into the next adjacent kiln, I provide a fan element 26.

The conduit 15 is in communication at one end with the passage way 14, and at its other end with the annular heat chamber 16 of the next adjacent kiln. The conduit 15 is provided with an opening 27 in its wall, 40 which has its side edges bevelled. A plate 28 having corresponding bevelled edges is received within the opening 27.

Extending through the plate 28 is the shaft 29 upon which the fan element is mounted. The shaft 29 may be operatively connected to a motor in any suitable manner. A collar 30 is on the shaft 29, which rests upon the ball bearing 31.

It will be seen that when the damper 22 is closed and the damper 23 is open, then the operation of the fan element 26 will cause the heat or products of combustion, which are in the conduit 15, to pass into the annular heat chamber 16. The heat will then pass up through the passage way 19 between the flash wall 11 and the outer wall of the kiln 10 and into the kiln proper.

The arranging of the fire pockets or grate structure 17 so that they alternate with the passage ways 19 is very desirable and causes the heat to be equally distributed in the kiln.

When the fan element 26 is in operation, the products of combustion or heat pass through one kiln in the direction indicated

by the arrows 24 and 25, into the conduit 15 and in the direction indicated by the arrows 32, and into the next adjacent kiln.

In order to permit cool air to pass in around the fan element 26 so as to prevent it from melting down, I provide openings 33 in the plate 28. A cover member 34 having an opening 35 therein is rotatably mounted on the plate 28. When it is desired to permit cold air to pass in around the fan element 26, I rotate the cover member 34 so that the opening 35 registers with the opening 33.

After the temperature in the conduit 15 reaches such a degree that the fan element will no longer stand up, I then move the entire fan element and plate 28. The opening 27 is then sealed with any suitable plate. The complete fan element unit may then be moved over to the next adjacent kiln and so on.

It is extremely necessary that the fan element unit be capable of removal from the conduit 15, in view of the fact that intense heat passes therethrough.

It will be seen that the fan may be so positioned, and the dampers 23 so regulated that heat will be drawn through several of the kilns 10 into the kiln adjacent to the fan element.

The plate 28 serves as a sealing member for the opening 27 and at the same time as a supporting member for the fan element 26, and also a support for a motor as it is desirable to connect the shaft 29 direct with a motor.

By my arrangement it is possible to conduct heat from the kilns through the entire battery of kilns. I can hardly over-emphasize the necessity of making the fan element removable, in view of the fact, that the heat which would pass through the conduits 15 would be so great that the fan element would melt down.

It will be understood that each of the kilns is "fired" in the ordinary manner and it may be said that it is superheated by the arrangement of drawing heat from one kiln into the next adjacent kiln.

My present invention is an improvement of my Patent Number 1,404,412, issued to me January 24, 1922.

Some changes may be made in the construction and arrangement of the various parts of my invention, without departing from the real spirit and purpose of my system of kilns, and it is my intention to cover by my claim, any modified forms of structure or use of mechanical equivalents, which may be reasonably included within its scope.

I claim as my invention:

A battery of kilns each provided with heating chambers and passageways arranged between the heating chambers and connected

together by a subterranean conduit, each of said conduits having an opening in the top wall thereof, a fan element arranged to be selectively and removably received in any one of the conduits between any pair of kilns, so that heated air from one kiln may be drawn into the next adjacent kiln, a bearing member for said fan element arranged to be seated in any of said openings, and when the kiln is at a predetermined heat the fan element and bearing member may be removed for the purposes stated.

Des Moines, Iowa, June 2, 1922.

LEROY WEEKS.
